UNITED STATES PATENT OFFICE

2,039,457

CUTTING MACHINE

Carl Schober, South Pasadena, Calif.

Application August 18, 1934, Serial No. 740,440

3 Claims. (Cl. 146—98)

This invention relates to cutting machines, and more particularly to a machine for cutting vegetables, such as string beans, into small pieces, for cooking and eating the same.

5 The general object of the invention is to provide a machine for cutting string beans and the like which is simple, efficient in operation and inexpensive.

10 A more particular object is to provide a cutting machine of the character stated which may be readily clamped upon the edge of a table for use, and unclamped and removed from the table when not in use.

15 Other objects and advantages will appear hereinafter.

The invention is illustrated in the annexed drawing which forms a part of this specification and in which,

20 Fig. 1 is a side elevation of my invention shown clamped upon the edge of a table in position for use, with its cutting mechanism extending over and above the table and with a bowl resting under said mechanism for receiving the vegetables cut thereby.

25 Fig. 2 is an end elevation of my invention.

Fig. 3 is a plan view of Fig. 1.

Fig. 4 is a fragmentary horizontal section of my invention taken on line 4—4 of Fig. 1.

30 Corresponding parts are designated by the same reference characters in all the figures of the drawing.

35 My invention comprises a horizontal frame 1, formed at one end with a depending supporting member 2 and a clamp 3 at the lower end of said supporting member; a cutting wheel 4 journaled in said frame; a grooved roller 5 journaled in said frame for coating with said cutting wheel; a crank 6 for rotating said cutting wheel; a scraper 7 for scraping the cuttings from said cutting wheel; and a guard 8 extending over a portion of said cutting wheel for protecting the hands of the operator of the machine from being cut by said cutting wheel.

40 45 The clamp 3 comprises a pair of spaced clamp members 9 and 10 and a clamp screw 11 seated in the member 10, which members are adapted to extend over the edge of a table 12 with the member 9 resting upon the upper side of the table and the member 10 extending under the table, so that the upper end of the screw 11 may engage the under side of the table and draw the upper clamp member 9 tightly against the upper side of the table for clamping the machine on

said table in position for use, as illustrated in Fig. 1 of the drawing.

The frame 1, supporting member 2 and clamp members 9 and 10 may be formed of a single piece of metal strap 13, which is bent at right angles at 14 and 15 to form an end member 16 at one end of said frame and side members 17 and 18 of said frame, bent inwardly at 19 and 20 to form end members 21 and 22 at the other end of said frame, which end members are 10 brought together and bent flat upon each other centrally of the frame 1 at 23, completing said frame, and the remaining portions of said strap twisted together at right angles at 24 and bent downwardly together at right angles at 25 to 15 form the supporting member 2, and the ends of said strap bent inwardly at right angles to said supporting member in spaced relation to form the clamp members 9 and 10 respectively.

20 The cutting wheel 4 comprises a plurality of cutting discs 26, a plurality of spacing washers 27 arranged between said discs and spacing the same apart in cutting relation, and a pair of end spacing washers 28 and 29 arranged at the ends respectively of said cutting wheel for spacing the discs at the ends of the wheel from the side members 17 and 18 respectively of the frame 1, said cutting discs and said washers all being tightly fitted on a drive shaft 30 which extends 25 transversely through the frame 1 with its ends journaled in said side members of said frame, whereby the cutting wheel 4 is mounted within the frame 1. The discs 26 are formed with sharp peripheral cutting edges 31. One end of the drive shaft 30 is formed with a threaded socket 32 and one end of the crank 6 is threaded as at 33 and screw seated in said socket, whereby said drive shaft and the cutting wheel 4 may be rotated by rotation of said crank.

30 35 40 The grooved roller 5 comprises a plurality of discs 35 and a plurality of spacing washers 36 tightly fitted on a shaft 37, which shaft extends through the frame 1 with its ends journaled in the side members 17 and 18 of said frame, whereby said roller is positioned in said frame to receive the cutting edges 31 of the cutting discs 26 of the cutting wheel 4 within the annular grooves 38 respectively of the roller, said grooves being formed between the roller discs 35 by the spacing washers 36 of such width that said cutting discs will be engaged with sufficient friction between the sides of said grooves to cause said discs, when rotated by the crank 6, to rotate the roller 5 for enabling said cutting discs to cut up 50 55

vegetables fed between the cutting wheel 4 and said roller 5.

The scraper 7 and the guard 8 are secured respectively to the under side and upper side of the frame 1 by a bolt 40 and nut 41, which bolt extends downwardly through said frame at the junction of the frame end members 21 and 22, and said nut screws on the lower end of said bolt against the scraper 7, whereby the rear ends of said scraper and guard are respectively secured against the lower and upper edges of said end members.

The scraper 7 is slotted rearwardly from its forward edge at 42 to receive the cutting discs 26 of the cutting wheel 4 and provide scraping teeth 43 which extend between said cutting discs and engage the sides thereof to scrape any cuttings from said discs which may adhere thereto. (See Fig. 4.)

The guard 8 extends over the rear portion of the cutting wheel 4 for protecting the hands of the operator while feeding vegetables to be cut between said cutting wheel and the cutting roller 5, and said guard is formed at its side edges with depending arms 44 provided with openings 45 in their lower ends through which extends the ends of the cutting wheel drive shaft 30, whereby the forward end of the guard 8 is supported and prevented from being bent down against the cutting wheel discs 26.

The operation, uses and advantages of my invention are as follows:

My cutting machine being clamped on the edge of a table 12 by the clamp 3, a bowl 50 or other receptacle is placed on the table under the cutting wheel 4 and its coacting grooved roller 5, as illustrated in Figs. 1 and 2 of the drawing. The operator feeds the vegetables, such as string beans, into the upper side of the machine between the cutting wheel 4 and the roller 5, and rotates the cutting wheel, by means of the crank 6, clockwise (see Fig. 1), whereupon the cutting wheel discs 26, in the roller grooves 38 in frictional engagement with the sides of the roller discs 35, rotate the roller 5 counterclockwise, and such coaction of the cutting wheel and roller causes the sharp peripheral cutting edges 31 of said cutting discs to cut the beans or other vegetables into small pieces, which drop from the cutting wheel 4 and roller 5 between the cutting wheel discs 26 into the bowl 50.

By means of my cutting machine a considerable quantity of string beans or other vegetables may be cut up into small and uniform pieces in a short time and with little effort or skill.

My cutting machine is particularly useful in

restaurants, hotels, institutions and other places where large quantities of string beans or other vegetables cut into small pieces are required for cooking and eating.

I claim as my invention:

1. A cutting machine comprising a piece of metal strap, bent to form a frame, a supporting member for said frame and a clamp for clamping said supporting member on the edge of a table with said frame above the table, said piece of strap being bent first at right angles at two points to form the forward end member and the two side members of said frame, then bent inwardly together and upon itself to form the rear end frame members, then twisted and bent downwardly to form said supporting member for said frame, and the ends of the strap then being bent inwardly to form the clamp members of said clamp, cutting means mounted in said frame for cutting vegetables so that the cut vegetables will drop into a bowl on the table below said frame, a guard mounted on said frame over the rear part of said cutting means, and a single bolt extending through said guard and through said frame at the junction of said rear end frame members, and a nut on the threaded end of said bolt for securing said guard in position on said frame.

2. A cutting machine as characterized by claim 1 in which the guard is formed with depending arms through which extend a shaft of said cutting means.

3. A cutting machine comprising a piece of metal strap, bent to form a frame, a supporting member for said frame and a clamp for clamping said supporting member on the edge of a table with said frame above the table, said piece of strap being bent first at right angles at two points to form the forward end member and the two side members of said frame, then bent inwardly together and upon itself to form rear end frame members, then twisted and bent downwardly to form said supporting member for said frame, and then bent inwardly near its ends to form the clamp members of said clamp, a cutting wheel and a coacting roller for said wheel journaled in said frame for cutting vegetables, a guard mounted on said frame over the rear portion of said cutting wheel, a scraper, for scraping the cutting elements of said cutting wheel, mounted on the under side of said frame, and a single bolt extending through said guard, frame and scraper at the junction of said rear end frame members and a nut on the threaded end of said bolt for securing said guard and scraper in position on said frame.

CARL SCHOBER.
